UNITED STATES PATENT OFFICE.

LEE LLEWELLYN, OF DORMONT BOROUGH, PITTSBURGH, PENNSYLVANIA, ASSIGNOR
TO PITTSBURGH COAL WASHER COMPANY, OF PITTSBURGH, PENNSYLVANIA, A
CORPORATION OF PENNSYLVANIA.

COAL-WASHING APPARATUS.

1,267,565.

Specification of Letters Patent.

Patented May 28, 1918.

Application filed January 5, 1918. Serial No. 210,415.

To all whom it may concern:

Be it known that I, LEE LLEWELLYN, a citizen of the United States, residing at Dormont Borough, South Hills Branch, 5 Pittsburgh, in the county of Allegheny and State of Pennsylvania, have invented certain new and useful Improvements in Coal-Washing Apparatus, of which the following is a specification.

10 My invention refers to improvements in washing apparatus for coal or other minerals for the separation of impurities by gravity and the buoyant effect of water, imparted in a series of pulsating movements.

15 The improvement relates particularly to the construction of the jig and a plurality of simultaneously operating co-acting plungers, as more fully hereinafter described.

The present invention is an improvement 20 in that type of apparatus disclosed in the patent of W. A. Knoyer #906,239 dated December 8, 1908.

Referring to the drawings,

Figure 1 is a central vertical sectional view through a coal washing apparatus provided with my improvement, the section being indicated by the line I—I of Fig. 2; and

Fig. 2 is a vertical sectional view on the line II—II of Fig. 1.

30 The apparatus comprises a jig tank 2, preferably rectangular in form having inwardly and downwardly sloping ends 3, 3, and a middle transverse partition wall 4. Said wall divides the interior space of the

35 jig tank at its upper portion into two substantially equal chambers, as to volume, and each chamber is provided at its lower portion with terminal collecting boxes 10, 10, for slate and other impurities. These com-

40 municate through one wall of the jig tank foundation by an opening 11 into a collecting tank 12, which may, if desired, be provided with an opening and a closing door 13 by which the refuse material may be dis-

45 charged from time to time.

In the upper portion of the chamber construction are mounted supporting screens 8, 8^a, of perforated plate metal, wire netting, or other suitable construction adapted to 50 support the mineral to be washed and to provide for free upward travel of the water therethrough, in pulsation, due to the reciprocating action of the several plungers mounted within the space below the screens.

Each screen is preferably arranged at a 55 slight angle as shown, lowering toward the center of the jig, which is provided with an upper partition wall 5 and suitable framing, whereby to separate each screen cavity into an individual space. Partition 5 extends upwardly sufficiently far to separate the screens, but not as high as the top edge of the jig, whereby to provide for the passage of washed coal thereover from screen 8 to the other screen 8^a. The screens are fixedly 60 mounted across the upper portion upon suitable supporting frames 9, 9, incorporated with the structure.

About midway of each screen, and between the screens in a position corresponding to the middle portion of the jig and partitions 4 and 5, I provide substantially fluid-tight casings 14 of plate metal or the like, within surrounding timber or other framing 15 of suitable construction. 75

A reciprocable shaft 16 is mounted in suitable bearings 17 within the jig, and a packed bearing 18 through one wall thereof, said shaft being actuated by an eccentric or other suitable mechanism 19 from a driving 80 shaft 20 of well known construction. Mounted within each casing 14 is a series of plungers *a*, *b*, and *c* respectively, preferably of varying cross area, and each fixedly secured to the shaft by collars as shown or otherwise, whereby to reciprocate in unison and to an extent controlled by the throw of the eccentric. 85

In the position shown in Fig. 1, the plungers are at their middle position, and will 90 reciprocate to the same extent in one direction and the other. Such reciprocation imparts a series of impulses to the plungers, by which a series of pulsations is produced, causing the water to surge upwardly 95 through the perforated screens, alternately at each side of each plunger. The plungers are preferably made of varying cross area, and with corresponding efficiency as to their volume of displacement. Thus, the middle 100 plunger *b* is of the largest area, being utilized to produce the heaviest pulsations and disturbance of water, while plungers *a* and *c* are relatively smaller, plunger *a* being preferably slightly larger than plunger *c*. 105

By this means I provide a more vigorous washing of the coal in the first screen 8 and a more quiet but sufficiently effective dis-

turbance and separation in screen 8. The passage of the washed coal from the latter screen is thereby facilitated without unnecessary agitation.

5 At the inner end of the first screen 8, I locate a slate gate 21, connected by pitman 22 and a suitable operating lever 23 by which the slate gate may be raised from time to time to release the accumulated 10 slate, etc.

10 A deflecting shield or guard 24 extends downwardly and inwardly from the framing construction at its middle portion, for the full width across the slate outlet opening 15 25, whereby to effectively protect the same from the effect of the pulsations of the middle plunger *b*. The plunger impelled water in such case will follow a direction generally indicated by the arrows, upwardly toward 20 the screen 8 and without materially affecting the slate outlet.

25 The raw coal is first discharged onto screen 8 where the main separation of the coarsest slate is effected, the slate accumulating on the screen and forming a movable bed. As the slate accumulates it may be discharged from time to time by gate 21. Also, some of the slate of the smaller sizes may 30 pass downwardly through the perforated screen bottom, the entire mass of slate at all times permitting free upward passage of the water.

35 Screen 8 is preferably covered with a layer of feldspar or other suitable material of sufficient specific gravity to rest upon the perforated screen bottom, preventing the downward passage of the finer particles of coal or other light minerals while permitting a free upward circulation of the water 40 under the impulses impaired to it by plungers *b* and *c*, permitting the heavier impurities, as slate, to fall down through the burden of the coal and on to the upper surface of the screen or of such lining material.

45 By imparting to the coal a continuous series of rapid pulsations by means of the plurality of coöperating reciprocable plungers, I effect a practically continuous washing and separating action of the water throughout 50 the entire area of the burden-supporting screens. By locating the supplemental plungers *a* and *c* about midway of the two main portions of the jig chamber, beyond the middle plunger, it is not necessary to depend 55 upon the action of the middle plunger alone, its pulsations being supplemented by those of the supplemental plungers and resulting in a very thorough application of the water. By this means, I effect a more rapid and 60 thorough separation of the impurities and thereby greatly increase the capacity of the jig.

The raw or unwashed coal is delivered to the receiving jig 8 from a bin or other supply by means of a chute 26 and the washed

coal passes outwardly of the jig at its other end through a depressed delivery channel 27, as will be readily understood. Water is supplied to the jig tank as required by suitable pipe connections 28.

70 It will be understood that the number and extent of the strokes may be varied to suit the character of the coal or other mineral; also, that the slope of the screens may be changed, as well as the relative size and proportion of the plungers, or that other changes or variations may be made by the skilled mechanic without departing from the scope of the following claims.

75 What I claim is:—

1. In a coal washing apparatus, a tank having a receiving and an outlet portion, a supporting screen arranged transversely of the tank, a plunger located below and at one end of the screen and another plunger located below and about midway of the screen respectively, and means for reciprocably actuating said plungers together.

80 2. In a coal washing apparatus, a tank having a receiving and an outlet portion, a supporting screen arranged transversely of the tank, a plunger located below and at one end of the screen and another plunger of different area located below and about midway of the screen, and means for reciprocably actuating said plungers together.

85 3. A coal washing apparatus comprising a tank having a middle transverse partition terminating below the top of the tank, a perforated screen arranged across the upper portion of the tank at each side of the partition and extending downwardly toward said partition at each side, an individual plunger framing between and below each screen respectively, a reciprocable shaft 90 extending through the jig chamber below said screens, a plurality of plungers mounted thereon each operable in one of said framings adapted to impart series of pulsations, and means for actuating said shaft.

100 4. A coal washing apparatus comprising a tank having a middle transverse partition terminating below the top of the tank, a perforated screen arranged across the upper portion of the tank at each side of the partition and extending downwardly toward said partition at each side, a reciprocable shaft extending through the jig chamber below said screens, a plurality of plungers of different areas mounted thereon adapted 105 to impart series of pulsations, and means for actuating said shaft.

110 5. A coal washing apparatus comprising a tank having a middle transverse partition terminating below the top of the tank, a 115 perforated screen arranged across the upper portion of the tank at each side of the partition and extending downwardly toward said partition at each side, a reciprocable shaft extending through the jig chamber below 120 said screens, a plurality of plungers of different areas mounted thereon adapted to impart series of pulsations, and means for actuating said shaft.

125 6. A coal washing apparatus comprising a tank having a middle transverse partition terminating below the top of the tank, a 125 perforated screen arranged across the upper portion of the tank at each side of the partition and extending downwardly toward said partition at each side, a reciprocable shaft extending through the jig chamber be- 130

low said screens, a plurality of plungers mounted thereon and having different areas adapted to impart correspondingly different pulsations toward the screens in different proportions as to selected portions thereof, and means for actuating said shaft.

6. In a coal washing apparatus, a tank having a receiving and an outlet portion, a pair of supporting screens arranged transversely of the tank, a plunger located below and between said screens, a plunger located below and about midway of each of said screens, and means for reciprocably actuating all of said plungers together.

15 7. In a coal washing apparatus, a tank having a receiving and an outlet portion, a pair of supporting screens arranged transversely of the tank, a plunger of maximum area located below and between said screens, supplemental plungers of reduced area located below and about midway of each of said screens, and means for reciprocably actuating all of said plungers together.

25 8. In a coal washing apparatus, a tank having a receiving and an outlet portion, a pair of supporting screens arranged transversely of the tank, a plunger of maximum area located below and between said screens, a supplemental plunger of reduced area located below and about midway of one of said screens, a supplemental plunger of further reduced area located below and about midway of the other of said screens, and means for reciprocably actuating all of said 30 plungers together.

9. In a coal washing apparatus, a tank having a receiving and an outlet portion, a pair of supporting screens arranged transversely of the tank, and sloping downwardly toward the middle thereof, an intervening upwardly extending partition, a refuse discharge opening between one of said screens and said partition, means for releasing accumulated refuse material from said screen, a shield extending across underneath said opening, a transverse partition located below the middle of each screen respectively, each of said partitions having a plunger casing, a reciprocable plunger in each of said casings, and means connected with each of said plungers adapted to actuate them together.

40 10. In a coal washing apparatus, a tank provided with an outlet conduit at one end, a middle transverse partition, a receiving screen sloping downwardly toward said partition with an intervening slate outlet space, a gate for said space, a protecting shield therefor, a similar delivery screen at the other side of the partition, a transverse partition below and between said screens and below the middle portion of each screen each having a plunger housing, a plunger operatively mounted in each of said housings, and means for actuating all of said plungers 45 together.

50 In testimony whereof I hereunto affix my signature.

LEE LLEWELLYN..
